ABSTRACT OF THE DISCLOSURE

A tap changer for transformers includes a regulating winding with a plurality of fixed contacts connected to different points thereof, these contacts being engaged by a movable contact. One of the fixed contacts constitutes a switching contact which is connected to the transformer winding. This contact is elongated and its length is greater than the distance the movable contact moves during a complete switching step. A change-over switch is also provided for changing over the connection between the transformer winding and the regulating winding.

BACKGROUND OF THE INVENTION

Field of the invention

The invention relates to tap changers of the selector switch type for transformers.

Tap changers of the selector switch type where the closing and breaking under load takes place in the selector itself are usually combined with a power accumulator, for example a spring driving device in order to ensure rapid and safe operation.

In selector switches with plus/minus switches it is necessary for the plus/minus switch to carry out its switching when the movable contact of the regulating selector leaves the fixed contact connected to the main winding of the transformer, the so-called switching contact, before it closes the connection to the next fixed contact. In some constructions this problem has been solved by dividing the movement of the movable contact of the plus/minus switch into two stages. However, the contact is then during a certain period situated in a position between the two fixed contacts of the plus/minus switch, with the regulating winding open at both ends, so that dangerous voltages may occur between the two ends of the winding.

Another solution of the problem which is not completely satisfactory either is that the movable contact of the plus/minus switch performs its switching separately, driven directly by the driving motor of a spring device, at the same time as the driving motor sets the spring device so that the plus/minus switch is in its switched-over position when the energy of the spring device is released for switching over the movable contact of the regulating selector switch to an adjacent contact. However, even in this case there is a risk that the regulating winding will be open if the movement of the driving device is not compelled to the point where the spring energy is released, for example in manual operation which is not completed or if for some reason the voltage of the driving motor should disappear.

There is also a risk with tap changers of the coarse/fine connection type that the regulating winding will remain open in a certain position of the change-over switch and also the disadvantage that almost the entire voltage of the regulating winding in certain control positions will be between the movable contact of one of the contact fingers in the regulating selector and a fixed contact of the

2

regulating winding for a distance which is considerably less than the distance between two fixed contacts.

SUMMARY OF THE INVENTION

The above mentioned disadvantages are completely eliminated with a tap changer according to the invention which relates to a tap changer for transformers comprising a regulating selector with regulating winding and movable contact and also a change-over switch for switching over the connection of the main winding of the transformer to the regulating winding, where one of the fixed contacts of the regulating selector, the switch-over contact, is connected to the main winding. The invention is characterized in that the switch-over contact is elongated so that it covers substantially a complete contact division of the regulating selector. During the connection step following that in which the movable contact of the regulating selector moves over the switching contact, the movable contact slides along the switching contact without any closing or breaking of the current taking place. During this step the change-over switch switches over and in known manner turns the voltage of the regulating winding 180° in relation to that of the main winding. Since the spring driving device drives both the movable contact of the regulating selector and that of the change-over switch, and since these two contacts are connected mechanically there is no risk that the regulating winding will remain open for longer than the time taken by the switching operation itself. The power used during the switch-over will be negligibly more than during a normal connecting step since during this connecting step the contact of the regulating selector glides along the switching contact and the necessary friction is negligible compared with the switching operation in the change-over switch. The invention thus enables the use of smaller spring driving devices.

In selector switches having one shaft and fixed contact fingers on the movable contact, during a connection operation at least one of these contact fingers will be situated in the gap between two fixed contacts and the distance between such a contact finger and the neighbouring fixed contact will be considerably less than the distance between two fixed contacts. During a certain part of the plus/minus switching operation, therefore, the entire voltage of the regulating winding will lie across the said short-distance, with the consequent risk of flash-over. With the selector switch according to the invention only the step-voltage can arise over said distance while the voltage of the regulating winding is over the distance between two fixed contacts.

BRING DESCRIPTION OF THE DRAWINGS

In the accompanying drawings FIGURE 1 shows the invention used for a tap changer with change-over switch. FIGURE 2 shows the invention used for a tap changer with coarse/fine connection and FIGURE 3 shows a third use of the elongated contact according to the invention.

DESCRIPTION OF THE PREFERRED EMBODIMENTS

In FIGURE 1 of the drawing the main winding of the transformer is designated 1 and the regulating winding 2. The main winding is connected at one end to the movable contact 3 of the plus/minus switch. The ends of the regulating winding are connected to one each of the fixed contacts 4 and 5 of the plus/minus switch. The contact 4 is marked with + and the contact 5 with — which means that when the contact 3 is in the shown position the voltages of the two windings are in the same direction, plus-connection. The movable contact 3 is journaled on a shaft 6. The regulating winding 2 has a number of fixed contacts 20, 21, 22, 23, 24,

25, 26, 27, 28 and 29 arranged in a circular path so that a movable contact 7 at the centre of the circular path can cooperate with each of them. The regulating winding 2 with its contacts and the movable contact 7 together form the regulating selector of the tap changer. The distance between each of the contacts 20-29 is preferably the same and is called a connection step. One end of the regulating winding 2 is connected to the fixed contact 4 of the plus/minus switch and the other end is connected to the contact 5. A switching contact 8 is arranged between the contacts 20 and 29, the length of which corresponds to a connection step and it is connected directly to the movable contact 3 of the plus/minus switch and thus also to the main winding 1.

The movable contact 7 in the regulating selector may be made in different ways, but in the shown embodiment it has a main contact 9 and two resistance contacts 10 and 11. The contact 10 is connected to the main contact 9 by a resistor 12 and in the same way the contact 11 is connected to the main contact by a resistor 13. A conductor 14 is connected to the movable contact 7 and to a point 15 which forms one end of the total phase winding. The other end of the phase winding is designated 16 and to this is connected the main winding 1.

The driving of the movable contacts 3 and 7 of the plus/minus switch and regulating selector, respectively, is coordinated and synchronized and takes place in a way known in principle. A driving motor sets springs in a driving device and when the impulse to the switch arrives the spring driving device is released and the contact 7 of the regulating selector moves forward one step. The contacts 3 and 7 are connected by means of a Maltese cross controlled by the contact 7 and influencing the plus/minus switch during only one step corresponding to the switching contact 8.

If the contact 7 of the regulating reflector in the position shown in the FIGURE 1 is moved one step in a clockwise direction the contact will slide on the switching contact 8 the whole time. When it starts to move the contact 3 receives a driving impulse and snaps over to its right-hand position. Thus during this connection step no switching over takes place in the regulating selector, only a plus/minus switching. The whole regulating winding is then disconnected. During all other connection steps switching over takes place in the regulating winding.

In the position shown in the FIGURE 1 only one step of the regulating winding is connected between the contacts 8 and 29 and thus also between the contact 8 and the resistance contact 10 on the movable contact 7. This voltage, step voltage, however, is so low that there is no risk of flash over. Between the contacts 8 and 20, however, is the entire regulating voltage, but since the contact 7 is at the left-hand edge of the contact 8, there is no risk of flashing over here either. Before the contact 7 during the previously described connection operation has reached the right-hand edge of the contact 8, the plus/minus has changed over and connected the contact 5 to the contact 8 so that there is now only step voltage between the contacts 11 and 20. It is thus seen that when full regulating winding voltage prevails between one of the contacts 20 and 29 and the movable contact 7 with its resistance contacts 10 and 11, the distance across which said voltage lies is as great as possible. This fact means that with the same diameter of regulating selector this can be used for considerably higher voltages than has previously been the case.

The main contact 9 of the movable contact 7 consists of two spring-loaded contact tongues which grip the flat fixed contact 20-29 and the switching contact 8, respectively, with considerable pressure in order to obtain good contact and low transition-resistance. This means that considerable force is necessary at switching over to press the two contact tongues apart so that they grip the stationary contact. This is also the case for the plus/minus switch. In known constructions both these operations take place simultaneously when the plus/minus switching is

to take place and the driving device must therefore be dimensioned so that it is capable of switching both the contacts 3 and 9 simultaneously.

FIGURE 2 shows a tap changer of the coarse/fine connection type. The switching contact 8 of the regulating selector is connected to a fixed contact 4 belonging to the change-over switch. This fixed contact is also connected to one end of the main winding 1 so that the switching contact 8 is permanently connected to the main winding. The other fixed contact 5 of the change-over switch is connected to the main winding at a certain distance from the end which is connected to the contact 4. The movable contact 3 of the change-over switch is journaled on the shaft 6 and is also permanently connected to one end of the regulating winding 2. Otherwise the tap changer is identical in construction and function to the type shown in FIGURE 1. Switching of the regulating winding takes place during a short time interval when the movable contact 7 of the regulating selector slides on the switching contact 8 and there is no operating position when the regulating winding is open.

In a tap changer according to the invention, therefore, no more than one switching ever takes place simultaneously. When the change-over switch switches from one position to the other the main contact 9 slides on the switching contact 8, but the effort necessary for this movement is considerably smaller than was the case with known constructions, but still operates satisfactorily.

FIGURE 3 shows another embodiment of the invention. As previously mentioned the tap changer is moved from one end position past the center position where the change-over switch switches when the movable contact 7 slides over the switching contact, and on to its other end position. The main contact 9 will then be situated on one of the fixed contacts 20 or 29 of the regulating winding. One of the resistance contacts 10 or 11 will then be in the gap between the switching contact 8 and the fixed contact 20 or 29, on which the main contact 9 is situated. This means that almost the entire voltage of the regulating winding will lie across the relatively short distance between the switching contact and one of the resistance contacts, with consequent risk of flash-over between them. The figure shows how the two contacts nearest the switching contact are extended so that in the same way they extend around substantially a complete contact division of the regulating selector. In this last connection position, when the voltage of the regulating winding is between the switching contact 8 and one of the contacts 20 or 29, the movable contact 7 of the regulating selector will be completely across one of the extended contacts 20 or 29 and have full insulating distance from the switching contact 8. There are cases, however, where the customer does not require more than, for example, 19 positions and in these cases nothing is lost.

I claim:

1. Tap changer for transformers including a regulating selector with a regulating winding and a movable contact and a change-over switch for changing over the connection between the main winding of the transformer and the regulating winding, one of the fixed contacts of the regulating selector constituting a switching contact connected to one end of the main winding of the transformer, said switching contact being elongated and its length being greater than the distance the movable contact moves during a complete switching step.

2. Tap changer according to claim 1, the fixed contacts of the regulating selector on both sides of and adjacent to the switching contact being elongated, the length of each of said two adjacent contacts being substantially equal to the length of the switching contact.

3. Tap changer according to claim 1, in which the change-over switch is of plus/minus type with a movable contact connected to one end of the main winding of the transformer and two fixed contacts, one of said fixed contacts being connected to one end of the regulating

winding, the second of said fixed contacts being connected to the other end of the regulating winding, the movable contact of the regulating selector lying on the switching contact during the time for the switching movement of the plus/minus switch.

4. Tap changer according to claim 1, characterized in that when the movable contact of the regulating selector is on the switching contact the movable contact of the plus/minus switch is connected to the end of the regulating winding at which the distance between the movable contact of the regulating selector and one of the adjacent fixed contacts of the control winding is least. 10

5. Tap changer according to claim 1 in which the change-over switch has a movable contact which is connected to one end of the regulating winding and two fixed contacts which are connected to different outputs of the winding of the transformer, characterized in that the switching contact of the regulating selector is connected to one fixed contact of the change-over switch. 15

6. Tap changer according to claim 5, characterized in that the switching contact is connected to the fixed con- 20

tact of the change-over switch connected to one end of the transformer winding.

7. Tap changer according to claim 5, characterized in that one end of the regulating winding is connected to the movable contact of the change-over switch.
